MACHINE FOR AND METHOD OF APPLYING
COVERS TO CONTAINERSAlbert F. Pityo, Clifton, N. J., assignor to Tri
State Cap & Cap Machinery Co., Inc., Newark,
N. J., a corporation of New Jersey

Application September 14, 1938, Serial No. 229,846

41 Claims. (Cl. 226—83)

The invention relates to new and improved methods and apparatus for applying covers to containers and more particularly to machines for applying covers of pliant material to containers, and especially such covers as hood covers or caps for bottles and the like. It is particularly concerned with the application to containers of a pliant covering material such as thick paper which is secured to the containers by shaping and folding parts formed integral with the material of the covers and which elements may also be assisted by suitable cement or adhesive means as distinguished in general from such auxiliary fastening devices as metallic means.

An object is to provide an improved container cover applying mechanism in which the cover applying means are of a non-rotary or stationary type. Certain aspects relate to the provision of a double or duplex capping mechanism and the association therewith of a particularly advantageous arrangement in feeding and transfer means adapted to operate on containers of the bottle type.

Further features reside in the improved means for feeding the blank covers or caps; in the provision of a cover applying mechanism for pleated hood covers having improved pleat forming means and the combination therewith of suitable skirt folders.

Another object is to provide a cover applying mechanism which includes improved means for folding or tucking one or more depending skirt tabs upward between the container neck and the adjacent skirt parts.

Still another object is to combine an improved pleat forming means with a plurality of folders including one or more folders of novel construction for tucking a depending skirt tab between the container neck and the skirt.

A further object is to provide a cover applying mechanism which includes a novel arrangement of folders of three forms, one for folding untabbed skirt sections, one for folding tabbed skirt sections and one for skirt tabs.

Another object is to provide a machine adapted for applying such covers in which certain of the contacting and securing parts are pre-coated with plastic cement.

A container cover applied in accordance with the principles and methods disclosed presents a smooth, attractive appearance and possesses ample strength for the purpose intended.

Other objects of the invention will in part be obvious and will in part appear hereinafter.

The invention accordingly comprises the sev-

eral steps and the relation of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a fuller understanding of the nature and objects of the invention reference should be had to the following detailed description taken in connection with the accompanying drawings, in which:

Fig. 36 is a detail plan of a portion of a similar blank showing the corner bending feature.

Fig. 37 is a perspective view illustrative of the initial folding operation.

Fig. 38 is a side elevation showing one of the hood covers applied on the neck of a container.

Fig. 39 is a detail-diagrammatic elevation somewhat enlarged showing the operation of the pleat guides, and

Fig. 40 is an enlarged transverse section of the carrier member and one of its eccentrics.

The preferred embodiment of the invention includes a suitable frame structure such as 2, on which is mounted a duplex container cover applying mechanism at the upper part and which mechanism is indicated in Figs. 1, 2 and 3 of the drawings by B. There are container feeding or supply means at the lower part indicated by C in Figs. 2, 4, 6 and 9, container transfer mechanism D shown in Figs. 4, 5, 6 and 9, and container discharge means E shown in Figs. 1, 2, 4 and 9.

The container feeding means comprise means for arranging uncovered or uncapped containers in contact in single file or series, and means to spread the containers apart sufficiently to present them at a proper distance to be acted on by the duplex cover applying mechanism B. The container transfer mechanism then delivers the containers in such spaced relation to the duplex cover applying mechanism B.

The cover applying mechanism then applies covers or caps simultaneously to a pair of containers, the transfer mechanism again functions to deliver them to the container discharge means and the container discharge means then removes them to a suitable place of delivery.

Referring to Figs. 2, 4, 5 and 6 it will be seen that the mechanisms B, and D are mounted on a base member such as indicated by 3 preferably

forming part of the frame structure 2 and which is preferably supported by columns or legs, such as 4. Preferably there is a motor unit for driving the machine and it can be of any suitable form such as indicated by 5 and may be supported in any suitable way as by mounting it on a shelf 6 secured to the legs 4 below the base member 3. Preferably the motor unit is provided with a speed adjusting means suitably operated as by the hand wheel 7, the turning of which causes the movement of a screw 8 by which the motor is moved to and fro and different speeds attained through the medium of an automatically adjustable tension pulley 9. The tension pulley 9 of the motor unit is provided with a driving belt 10 carried around a driven pulley 11 secured to the shaft 12 of a speed reduction unit 13. On the shaft 12 is also secured a worm 14 which drives the worm wheel 15 secured to the lower part of the vertical shaft 16 which is journaled in bearings 16a in the speed reduction unit. The shaft 16 also has secured to it at its upper part the bevel gear 22.

Journaled in a bearing 18 on the same axis as the shaft 16 is a vertical shaft 17 on which are secured two cams 19 and 20, and a spur gear 21. There is a coupling member 23 secured to the shaft 16 just above the bevel gear 22 between the latter and the cam 20 to which it is secured by bolts 23a.

Mounted on the base member 3 is a reciprocating carrier member 24 forming the base part of the transfer mechanism. This may be supported for reciprocation in any suitable manner but preferably as follows: Located in the base member 3 are two vertically arranged bearing sleeves 25 which journal the vertical shafts 26. Secured to the upper parts of each shaft 26 is an eccentric 27 having a shoulder 28. The securing means 30 comprises a hub 29 having a flange 29a to which the eccentric 27 is fastened by means of a screw 30 and pin 30a. There are two rectangular blocks 31 each block being made to fit the rabbets 32 of the depending longitudinal flanges of the member 24 and retained by the strips 24a. Each eccentric 27 is rotatively mounted in the circular bore 33 of its respective block. The member 24 can therefore be caused to slide along the blocks 31 which are suitably spaced apart as shown in Fig. 8.

The cam 20 causes the longitudinal movement of the member 24 through the medium of the anti-friction roller 34 mounted on the short arm 35 which is secured to the lower end of the vertical shaft 36 journaled in the bearing hub 37 of the base member 3. On the upper end of the shaft 36 is secured the long arm 38 to which is pivoted the link 39 said link being pivotally connected to the member 24 at 40. Thus rotation of the cam 20 causes oscillation of the arm 35, shaft 36 and arm 38 and consequent lengthwise reciprocating movement of the member 24.

Transverse reciprocation is also imparted to the member 24 at certain times by the mechanism shown in Figs. 5, 7, 8 and 12. At the lower end of each of the vertical shafts 26 is secured a pinion gear 41 which meshes with the teeth of a rack bar 42. The rack bar 42 is slidable to and fro in the channel of the bar 43 suitably secured to the frame structure 2, said bar 42 being just above the plane of the top of the cam 20. There is a bell crank 44 pivoted at 45 to the base member 3 and having an anti-friction roller 47 movable by the cam 20 on the side of the shaft 17 opposite the roller 34. Pivoted to the rack bar 42 at 48

is a connecting rod 49 on which is slidably secured a block 50 which is pivoted at 51 to the bell crank 44. A pair of spaced tension springs 49a urge the rod 49 in the direction to cause the shoulder 49b on rod 49 normally to be maintained in engagement with the block 50. The construction provides a safety feature to prevent breakage. The cam 20 oscillates the bell crank 44 by the roller 47 and said bell crank moves the rack bar 42 by means of the rod 49. This in turn rotates the pinion gears 41 which in turn revolve the eccentrics 27 simultaneously, these in turn moving the blocks 31 transversely of the longitudinal parts of the member 24 and moving it transversely. Thus the cam 20 causes both the longitudinal and the transverse movements of the carrier 24.

On the upper side of the member 24 are two bosses 53 and journaled in each boss is a vertical shaft 54. On each shaft 54 is pivoted a container holder which may be of any suitable form but preferably such as indicated at 55 in Figs. 4 and 9. The form there shown has two branches 56 and 57, each branch having a concave recess 58 adapted to receive and center a container when brought against it. Containers *k* are delivered spaced in pairs to the left hand holder 55 so that when the member 24 reaches the end of its left hand longitudinal movement, its left hand container holder 55 will have the recesses 58 of the respective branches 56 and 57 opposite two spaced containers *k*. When the member 24 reaches the end of its left hand longitudinal movement it moves toward the front of the machine and the left hand holder 55 engages with said pair of containers.

Forward of the carrier member 24 is a container guide or chute 59 which is in alignment with the cover applying heads F and G. An endless chain container conveyor 60 driven by the sprocket wheel 61 (see Fig. 20) secured to the shaft 62, is assembled in and below the chute 59 so that containers will be moved by the conveyor 60 towards said cover applying heads, guided by the two sides of the chute 59. The sides of the chute are cut away adjacent the carrier member 24, and at the forward side of the chute and operating partly over the same are devices, herein-after mentioned as the container separating devices or escapement, to space the containers apart and advance them in such spaced relation to the carrier member 24.

The container spacing device or container escapement embodies a member such as 63 movable transversely toward and from the advancing containers on the conveyor 60. The member 63 is preferably oscillatory and is secured to the sleeve 64 which is journaled in the frame casting 65. There is an arm 66 also secured to the sleeve 64 and having an anti-friction roller 67 which engages the cam 68 secured to the vertical shaft 69 and rotating therewith, said shaft 69 being suitably journaled in the frame casting 65. A coil spring 70 connects a pin 66a on the arm 66 to a pin 71 on the frame structure 65.

There is also a yieldable oscillating member 72 which moves on the same axis as the member 63 and which is carried on a shaft 73, passing through and journaled in the bore of the sleeve 64. The said shaft 73 passes farther downward, and has secured to its lower end an arm 74 carrying an anti-friction roller 75 by means of which it is oscillated by the cam 76 secured to the shaft 69. A coil spring 77 connects the arm 74 to the pin 78 on the frame casting 65.

The member 72 is pivotally mounted by a pin 79 on the member 80 secured to the upper end of the shaft 73, and there is a compression coil spring 81 which normally holds the member 72 against a stop 82 so that said member can yield by compression of the spring 81.

On the shaft 69 is a star wheel 83, held against the collar 69a by means of the compression coil spring 84, the wheel 83 having studs 83a which 10 normally engage the depressions 69c in the collar 69a. There is a shaft 85 suitably journaled in the frame casting 65 at the right of the shaft 69. Secured to the upper end of the shaft 85 is a one tooth container pusher 86.

15 The shafts 69 and 85 are driven through mechanism actuated by the bevel gear 22 on the shaft 16. The said gear 22 meshes with the mating bevel gear 87 secured to the shaft 88, on the opposite end of which is secured the sprocket wheel 89.

20 The sprocket wheel 89 drives the sprocket wheel 90 by means of the chain 92, and said wheel 90 is secured to the gear 93 and both secured to the shaft 91. The gear 93 drives the gear 94, the gear 94 drives the gear 96 which rotates on the 25 stud 97, the gear 96 is secured to the bevel gear 98 and the latter drives the bevel gear 99 secured to the shaft 85. The gear 96 meshes with the idler gear 100 which rotates on the stud 101 and said idler rotates the gear 102 rotating on the 30 stud 103. Secured to the gear 102 is the miter gear 104 which meshes with the miter gear 105 secured to the shaft 69. There is a sprocket wheel 106 secured to the shaft 91, which drives the sprocket 107 by means of the chain 108. The 35 sprocket 107 is secured to the shaft 62 and thus drives the sprocket 61 of the conveyor 60.

The cam 19 operates the means for raising and lowering the containers and maintaining them at the proper heights for applying the cover 40 blanks. The means I prefer to employ for accomplishing this result include two vertically movable plungers 110 (see Fig. 10) moved by a bifurcated lever 111 pivoted at 112 to a lug 113 on the under side of the base member 3, and actuated by the anti-friction roller 114 in the slot 45 of the cam 19.

The container lifters or plungers 110 are arranged respectively opposite the two cover applying heads or mechanisms F and G, and have 50 flatted parts 116 to engage the respective branches 117 and 118 (see Fig. 11) of the lever 111. They have vertical bearings in the slotted housings 119 secured on the base member 3 and are provided with tubular upper parts 120 on 55 which the tubular outer members 121 are slidably supported by resilient means consisting of helical springs 122 coiled around the short rods 123 secured to the plates 126 and extending down into the bores of the plungers 110. The plates 60 126 are secured to tubular parts 120 by screws 126a. The members 121 are held in the position shown in Fig. 5 by the internal collars 124 engaging the shoulders 125 on the plungers 110.

The mechanism of the double cover applying 65 means is preferably located in and on a casing such as 127 and the casing is preferably mounted on the flange 128 formed on the upper end of the tube 129, which is slidable up and down within the tube 130 which has a flange 131 by means of 70 which it is secured to the upper part of the base member 3 by suitable means such as the bolts 132. The upper end of the tube 129 has a key 129a which slides in the spline 130a and is thus prevented from turning. The lower part of the 75 tube 129 has an internal screw thread 133 which

fits the external screw thread on the tube 134 rotative within the tube 129.

Within the tube 134 is a tube 135 fixed against rotation by having its lower end pressed into the base member 3, and said tube has bearing portions 136 at its upper and lower ends. The said bearing portions journal the shaft 137 which has a tubular upper part 138 provided with a slot 139. In said tubular part 138 is the lower part of the shaft 140 journaled in the flanged part of the tube 129 and extending upward into the casing 127. A key 141 secured to the shaft 140 and fitted to the slot 139, causes the shaft 140 to be driven by the shaft 137.

At the lower end of the shaft 137 is secured a gear 143 which meshes with the spur gear 21 for driving the cover applying mechanism in and on the casing 127. At the upper end of the shaft 140 is secured the cam member 144 which has a box cam slot 145 in its flanged part 146, a gear 147 secured to the upper side of the latter, and a cam 148 secured to its hub 149. The gear 147 meshes with a smaller gear 150 secured to the hub 151a of the main cam member 151.

For raising and lowering the cover applying mechanism for different sized containers a horizontal shaft 152 is provided, said shaft being squared at 153 for application of a crank or other implement for turning it and having a bevel gear 154 secured to its inner end. The bevel gear 154 meshes with the larger bevel gear 155 keyed to the lower end of the tube 134 so that on turning the horizontal shaft 152 the tube 134 is caused to rotate and to move the tube 129 and with it the casing 127 and cover applying mechanism. A set screw 157 is provided to hold the shaft 152 from being turned when not desired.

Cover applying heads

Secured to the fixed part 121a of the casing 127 are right and left hand brackets indicated by 158R and 158L which serve to support the cover applying heads or devices. Each of said brackets has a horizontal part 159, a tubular part 160 rising from the part 159, and an upwardly extending flange 161 by means of which it is fastened to the part 121a by means of bolts 162. The tubular portion 160 contains the slidable tube 163 which in turn contains the slidable rod 164 of the blank holder 165. The blank holder 165 is preferably formed as a disk on the end of the rod 164 having a low annular flange 166.

Secured to the horizontal part 159 of each of the brackets 158R and 158L is a hub 167 preferably held thereon by screws 167a. The hubs 167 and the parts 159 have radial slots 168 and 168a in which certain of the skirt folders are mounted. Each hub 167 also has a depending annular flange 167c within which is formed an annular recess 167d adapted to hold the reciprocatory annular disk 169 on which the tab folders are mounted.

The folders are preferably of three forms, one form such as indicated by 170 for effecting the initial folding of the cover blank and preferably for folding untabbed or tableless sections of said blank. Another or second form of folder is indicated by 171 and is preferably for folding tabbed sections of the blank. The folders 170 and 171 alternate with each other and are ordinarily spaced around the container axis opposite the respective sections of the cover upon which they operate. There is a third form of folder such as indicated by 172 preferably for effecting the greater part of the folding or tucking in of depending peripheral tabs,

between the container neck and the adjacent skirt parts. In the present machine there are four of each form of folders for each of the heads F and G.

5 Each of the folders 170, hereinafter referred to as those of the first form, is constructed as a lever of the first order and has an actuating portion such as 173 which carries an anti-friction roller 174, for operating the folder by cam means which will be hereinafter described, a pivotal portion 175, and a folding portion 176. The latter consists of an end part or point 177 and a pressing surface 178 which is preferably concave at the upper part and convex at the lower part. Below the latter is an angular portion ending at the point 177. Through the pivotal portion 175 passes the pivot 175a fixed in the hub 167 on the bracket 158L or 158R and on said pivot the folder can oscillate. Each of the folders 170 has a spring plunger 179 for retracting it.

Each of the folders 171 referred to as those of the second form, is preferably a two part folder consisting of an actuating part 180 on which is mounted a working or folding part 181. The actuating part 180 consists of a lever of the first order pivoted by the pivot 182 fixed in the hub 167 of the bracket 158L or 158R. At its upper end there is an anti-friction roller 183 for operating the folder by cam means which will be hereinafter described. The folding part 184 is formed as a curved lever of the first order pivoted at its middle part on the lever 180 by a pin 185. The lever 184 is curved at its lower part toward the axis of the cover applying head and its lower end is provided with folding surfaces 186. The upper part of the lever 184 has a bore 187 in which is mounted a spring plunger 188 which serves to press the upper part outwardly and the lower part inwardly towards the axis of the head. The part 184 is preferably provided with a groove 191 in which the lower part of the lever 180 lies. It also has a narrow slot 192 extending to its lower end and has portions 193 for operating pleat pressers hereinafter to be described. 45 There is a bolt 194 screw threaded into the lever 180 and passed through a perforation 184a in the part 184. Nuts 195 permit adjustment to vary the tension on the spring plunger 188 to be adjusted and to vary the initial folding position of the lower end of the folder 171.

There is a third form of skirt folder denoted by 172 which is employed to tuck peripheral skirt tabs between the container neck and the adjacent skirt parts. The folder 172 has a pivotal portion 196, an actuating portion 197 and a folding portion 198 having the inwardly pointing hook 199. The folder 172 is pivoted by a pivot pin 200 in a slot 201 in the disk 169 which disk is movable vertically in the recess 167d. The lower part or hook of each folder 172 is placed in the slot 192 of one of the parts 184 and moves to and fro therein. The actuating parts 197 of the folders 172 lie in the annular groove 202 formed between the collars 203 at the lower end of the tube 163. As said tube is moved up and down by the lever 209 the folder 172 is oscillated so as to move the tabs of the cover blanks. The collars 203 lie in an annular recess 204 of the disk 169 and when the upper collar 203 moves upward far enough it engages the shoulder 205 in the disk 169 so that the latter also moves upward carrying with it the folders 172.

In the upper part of the casing 127 are located four short fixed shafts 206 on which are pivoted

four levers denoted respectively by 207, 208, 209 and 210.

Three of the levers 207, 209 and 210 are operated respectively by the upper cam path 211, the cam slot 212 and the lower cam path 213 of the main cam member 151. A return spring 214 is provided for the lever 207 so that it will always follow the cam path 211.

Each of the levers 207, 209 and 210 has two branches at the front (shown in Fig. 1), so that the two cover applying heads F and G are operated simultaneously from the main cam member 151. The levers 207, 209 and 210 are each provided with an anti-friction roller 215 at their cam contacting ends. There are two levers 208 one for each head F and G, each of which levers has an extension 216 for a purpose hereinafter to be described.

Each blank holder rod 164 has a screw threaded upper part and there is a screw threaded grooved collar 217 placed thereon, said collar therefore being adjustable up and down on said rod and connected with its lever 208 by means of shoes and pins 218 secured in the ears 219 at the lever ends. Downward movement is given to each blank holder and its rod by the lever 207, the right hand end of which bears on the adjustable collar 217 and upward movement of the blank holder and rod is caused by the upward movement of the container.

Secured to the upper part of the tube 163 is a grooved collar 220 the groove of which is engaged by the shoes and pins 221 secured in the ears 222 of the lever 209. Thus the operation of the tab folders 172 is actuated from the cam slot 212 and effected through the various connections therefrom as above described.

Slidably mounted on the tubular part 160 of each bracket 158L and 158R is a cam member 223 having a plurality of cam elements 224 and 225 the former being wedge shaped, the latter being preferably slotted or box cams, which are respectively adapted to operate the folders 170 and 171. Slidable on the tubular portion or sleeve 230 at the upper part of the cam member 223 is the annular operating member 227 which is connected to the lever 210 by means of shoes and pins 228 secured in the ears 229 of said lever. The operation of the cam member 223 is effected by the lever 210 when moved by the lowermost cam path 213. There is a flange 231 at the upper end of the sleeve 230 and there are coil springs 226 between the member 227 and flange 231 which normally hold the annular member 227 in its downward position. Pressure of the lever 210 compresses said springs at each stroke so that variations in the sizes of containers are accommodated without derangement or breakage of any operating parts. Thus the difference in diameters of pint and quart bottles is readily taken care of without readjustment of any part of the mechanism.

Mounted on the depending annular flange 167c of the hub 167 of each of the brackets 158L and 158R is a plurality of depending brackets 232 spaced apart on opposite sides of planes carried through the centers of folders 172.

Pleat guides 233 connected by portions 234 are secured to the brackets 232 and inward of each portion 234 is a movable pleat presser 236 pivoted at 237 in each bracket 232 and provided with an outwardly extending actuating part 238. The latter part is adapted to be engaged by the parts 193 on the folders 171 so as to oscillate the inner parts of the presser 236.

Blanks for the covers applied by this machine are provided in rolls adapted to be carried by reels such as indicated at 240, preferably journaled on non-rotating shafts 241 secured to brackets such as 242 bolted to the casing 127.

Journaled in suitable bearings 243 secured to the casing 127 are feed shafts 244 each having a ratchet wheel 245 secured to its rear end. Each of the ratchet wheels is operated by a pawl 246 mounted on the member 247 which is oscillated by the reciprocating slide 248 to which it is connected by the shoe 249 mounted on the pin 250 on the slide and slidable in the slot 251 of the member 247. The slide 248 is provided with an anti-friction roller 252 by which it is reciprocated by the cam 148. A coil spring 253 causes the return movements of the slide 248 and member 247, and a pawl 254 pivoted on the casing 127 prevents backward movement of the ratchet wheel 245.

On the outer end of each shaft 244 is secured a blank feeding wheel 255 provided with teeth 256 to engage the blank strip, and two annular grooves 257 one near each edge of the wheel. Below each feed wheel toward the cover applying head with which the wheel is associated, is a blank strip chute 258 having a channel 259 and blank strip guides 260. The chute 258 is secured to the bracket 261 of the cutting off device. The top plate 262 is provided with ears 263 which are bent upwardly and engage in the grooves 257 of the feed wheel 255. The lower plate 264 of the chute is bent downward at 264a and together with the ears 263 permits the end of a blank to be readily inserted when applying a fresh strip of blanks.

There is a blank tension device 265 constructed of three arcuate strips 266 separated by slots 267 and at the ends by bushings 268, the ends of the strips and bushings being held by pins 269, the lower pin mounted in brackets 270 secured to the chute 258 and the upper one secured to the hooks 271 of the hand lever 272.

Located above each feed roller is a roller 273 which serves as a printing bed for a dating device. Above the roller 273 is the printing cylinder 274 of said device and 275 is the ink fountain with an ink roller 276 mounted thereon. The cylinder 274 is connected to a sprocket wheel 277 driven by a chain 278 which in turn is driven by the sprocket wheel 279 secured to the shaft 244. A spur gear 280 connected with the gear 281 on the cylinder 275 serves for driving the latter.

Means are provided for locking the blank feeding mechanism when no containers are being fed, or when the supply is stopped for any reason. There is a locking pin 283 mounted for vertical movement over the slide 248 said pin being provided with collars and a groove 284 between them. A forked locking lever 285 is placed adjacent the groove 284 so that a pair of pins 286 on said lever will engage in the groove. The lever 285 is pivoted at 285a and its unforked end is held up by the spring plunger 287 and is adapted to engage the vertical rod 288 which is in engagement with the projection 216 of one of the levers 208. As illustrated in Fig. 14 it will be seen that when a container is ready to have its cover applied, the blank holder 165 is moved upward by the container, causing the upward movement of the lever 208 and downward movement of the projection 216, rod 288 and movement of the lever 285 to release the pin 283 from the notch 290.

Each of the levers 208 is moved downward each time that the lever 207 moves down actuated by the cam 151. Consequently the pins 283 lock the slides 248 in their outward positions each time they are moved by the cam 148. It is obvious that they will remain so locked unless the blank holder 165 is moved upward, which only takes place when a container is moved up against it. Thus the pin 283 causes the locking of the actuator slide 248 during such time as the supply is interrupted for any cause and the pawl 254 locks the ratchet wheel 245 and thereby the feed wheel 255 against backward movement at any time.

Each cover applying device or head has an automatic means for centering the containers, said means being actuated by the box cam slot of the cam member 144. A lever 300 provided with an anti-friction roller 301 is secured to the upper end of the shaft 302 journaled in the casting 127 and having a spring arm 293 at its lower end (see Fig. 18). The said spring arm 293 has a slot 293a into which projects a pin 304a secured to the gear 304. The latter meshes with a gear segment 305 which forms part of a centering arm 306 pivoted at 307. A second centering arm 308 is pivoted at 309 and has a gear segment 310 meshing with the segment 305, so that oscillation of the spring arm 303 caused by the movement of the lever 300 when actuated by the cam member 144 causes the centering arms 306 and 308 to be oscillated in opposite directions to grasp and center a container.

Fig. 35 illustrates one form of cover blank for use in the present machine. The said blank consists of a central portion 312, tabbed skirt sections 313, untabbed skirt sections 314, and peripheral tabs 315. There is also a tearing tab 314c on one of the sections. The sections are separated by scored lines 317. Fig. 36 illustrates a portion of the blank in which there are bent up corner portions 318 at the outer parts of the alternate sections 314. These are triangular in form and are scored in this form so as to give way when folding the tabs 315.

The means for forming the triangular portions 318 on the cover blanks are particularly illustrated in Figs. 18 and 19. Secured to the brackets 158R and 158L are the cut-off brackets 261 which carry the cutting-off levers 320 and knives 321. The latter have recesses 321a which form the tearing tabs 314c. Each of said levers is pivoted at 322 and normally held in open position by a spring plunger 323. Mounted on each bracket 261 is an operating rod 324 which is adapted to be pushed down by the projection 325 on the cam member 223 (see Fig. 2). Each bracket 261 is secured to one of the blank chutes 258, and has a lever 326 pivoted at 327, and bearing on the cross member 328 by its longer branch and engaging in a flattened portion 329 by its shorter branch. The cross member 328 is connected to the plate 330 below the chute 258 and said plate is pivoted on the pin 269 in the bracket 270. Mounted on the plate 330 are corner bending projections 331. These may be located at all four sides, or, as shown in Fig. 18, the rear projection 331a may be designed to bend the corners of two adjoining blanks.

Above the chute 258 is a plate 332 carried on a vertical member 333 having a bearing 333a in the bracket 261. There is a connecting member 334 clamped to the rod 324 and engaging with the vertical member 333 so as to move the latter and the plate 332 up and down. On the plate 332 are corner bending projections 335 cooper-

ative with the projections 331 on the plate 330 for forming the corner portions 318. Downward movement of the rod 324 causes the knife 320 to shear off the blank b and at the same time to form the tear off tab 314c and causes the plate 330 to move upward and the plate 332 to move downward so that the bending projections 331 pass close to the projections 335 bending up corner portions as seen at 318 in Fig. 36.

10 Referring to Figs. 35 and 36 it will be noted the blanks b are illustrated as having certain parts coated with an adhesive material on one side. In these figures stippling indicates the adhesive material which may be of any suitable plastic compound or may be of a compound that softens by heat treatment, in which case suitable heating means will form part of the cover applying mechanism but is not herein shown. In my present application the folding together and compressing of the skirt parts effects adhesion of the coated parts to each other. Preferably the adhesive is waterproof and so also is the material of the covers.

The operation of my improved machine for applying covers to containers is as follows:

25 Power being applied to the motor unit 5 causes the rotation of the tension pulleys 9 thereof, which in turn causes the rotation of the pulley 14 of the speed reduction device 13 by means of the belt 10 connecting them. The worm 15 on the horizontal shaft of the latter device causes rotation of the worm gear 14, shafts 16 and 17, cams 19 and 20, and gears 21 and 22 on said shafts.

30 The cam 20 causes oscillation of the short arm 35, shaft 36, and long arm 38 thereby producing lengthwise reciprocation of the carrier member 24 by the connection of the same to the arm 38 by the link 39.

35 Transverse movement is also imparted to the member 24 from the cam 20 through the bell crank 44, to the connecting rod 49, thence to the rack bar 42 and pinions 41, causing the latter to rotate to and fro, so that the eccentrics 27 are rotated in such manner that the blocks 31 within the member 24 are reciprocated simultaneously.

40 The bevel gear 22 on the shaft 16 by means of the connections hereinbefore described causes the sprocket 61 (see Fig. 20) to move the container conveyor 60 and to rotate the shafts 69 and 85. The movement of the conveyor 60 carries along a series of contacting containers, such as bottles, and as the leading container comes opposite the escapement device H, the two oscillating members 72 and 63 thereof are moved by the connections hereinbefore described toward and from the path of the containers. If said two members move so as to come between two containers as shown in Fig. 4 and member 72 does not come on a diametral line of the rearward one, the two containers k-1, k-2 will be separated sufficiently for the leading one to be advanced by the star wheel 83, and then by the rotating member or container pusher 86 to the positions as shown in Fig. 4 where the two leading containers k-1 and k-2 are opposite the left hand holder 55 on the carrier member 24 which has reached its extreme left hand position. The member 24 and the holders 55 are immediately moved forward and then moved toward the right so that the two containers k1 and k2 are gripped and pushed along to the right until they come to the two container lifters or plungers 110.

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

two containers so that each will contact with a blank *b* on the end of a strip *S* coming from one of the reels 240.

The rotation of the gears 21 and 143, and shafts 137 and 140 causes the rotation of the cam member 144 and cam 148, and the latter effects the movement of each of the slides 248, oscillating members 247, pawls 246, ratchet wheels 245 and shafts 244 and consequent feed of the blank strips *S* by means of the wheels 255. The end blank *b* is thus brought over the mouth *n* of a container *k3* or *k4*. The said container is being raised to a fixed position by the lifter 110 is then centered by the centering arms 306 and 308 and the plunger 165 then clamps the blank *b*.

While the blank is so clamped it is cut off by the knife 321 on the lever 320. The corner portions 318 are also formed on the next succeeding blank as described in connection with Figs. 18 and 19. The tearing tab 314c was cut when the cut-off took place. The container is moved upward still farther and causes the upward movement of the blank holder 165 and the mechanism hereinbefore described to lock the slide 248 is moved to trip the pin 283.

The cover blank *b* is now in the position illustrated in Fig. 30 with the blank holder 165 holding the blank on the container mouth by its central part 312, the tableless skirt sections 314 and the section 314a containing the tearing tab 314c are engaged by the points 177 of the folders 170 as illustrated in Fig. 37. The folders 170 four in number, have folded downward the corresponding four sections of the blank *b*. In consequence of the scorings which define the tabbed sections 313 partial folding of the pleats 316 is also effected, together with partial folding of the tabbed sections 313 but after the sections 314, 314a, which alternate with them.

Rotation of the main cam member 151 now causes the cam member 223 to move upward and thus causes the folders 171 to operate and to move their lower ends inward. The container is still moving upward and the pleat folders 233 now function to define the pleats 316 out of the triangular parts 316a, these parts 316a being moved upward against the folders or guides 233 as illustrated in Fig. 39, and the pleat pressers 236 are moved by the parts 193, finally pressing down the pleats. At this time also the folders 170 recede from their first position because of the concave portions of the cam 224.

The folders 172 are now brought into operation and move to the position in Fig. 32 by the upward movement of the tube 163 brought about by the collar 220, lever 209 and cam slot 212. The collars 203 are thus moved upward until the upper collar engages the shoulder 205 of the disk 169.

Fig. 33 illustrates the further operation of the folders 172 which are in the same relation to the container axis as in Fig. 32 but the hook portions 199 have been raised by the upward movement of the disk 169 caused by the lever 209 and cam slot 212. Figs. 32 and 33 show the effect of the hooks 199 on the tabs 315, which is to first move their ends to contact with the container neck *n* but slanted downward. Farther movement causes the tabs to slant upward. The final movement for bringing the tabs between the container neck and the skirt is by inward movement of the lower end of the folders 171 and parts 186.

This is illustrated in Fig. 34 where the folders 170 and 171 are both shown in their final or pressing position, the folders 172 being retracted. 75

The adhesive is not sufficiently sticky to adhere to smooth paper or other pliant material of which container covers may be made but if two adhesive surfaces are put against each other and a moderate pressure applied, the two coated surfaces will adhere, so that for instance if the tabs 315 are put against the surfaces of the sections 313 immediately adjacent the bend line they will adhere strongly when the folders 171 press the covers against the container necks.

Fig. 9 illustrates the escapement for containers in a position where rapid feed of containers would otherwise result in jamming of the container when being transferred to the carrier 24. 15 The drawing in said figure shows how the member 72 yields when its point is brought against a container on a diametral line. Oscillation of the member 63 may then cause the container to be pushed back a small amount so that on the 20 reverse movement of member 63, the held back container is carried along by the conveyor 60 into the star wheel 83.

The linear speed of the endless chain conveyor 60 is somewhat greater than that of the 25 lengthwise speed of the carrier 24. The speed of the latter is less than that of the discharge conveyor in E, which ensures that the covered containers shall be promptly taken away from the cover applying heads.

30 Since certain changes in carrying out the above method and in the construction set forth, which embody the invention, may be made without departing from its scope, it is intended that all matter contained in the above description or 35 shown in the accompanying drawings shall be interpreted as illustrative and not in a limiting sense.

Having described my invention, what I claim as new and desire to secure by Letters Patent is:

40 1. Container cover applying mechanism embodying skirt folders of three forms, one form effective for folding tabbed skirt sections, one form effective for folding tableless skirt sections and one form effective for folding skirt tabs, 45 fixed supporting means for the first two forms of folders and movable supporting means for the tab folding folders.

2. Container cover applying mechanism embodying movable folders of three forms, fixed 50 supporting means for two forms of said folders, actuating means for said two forms of folders, movable supporting means for the third form of folders, and actuating means for said third form of folders.

55 3. In a mechanism for applying a skirted cover having tabbed sections to a container, means for folding down sections of said skirt against the container neck, and means for upwardly tucking the tabs between the skirt and the container 60 neck comprising a pivotally mounted tab folder, means for operating said folder to move the respective tab inwardly, and means for upwardly shifting the folder pivot to complete the tucking operation.

65 4. Container cover applying mechanism embodying skirt folders of three forms, one form effective for folding tabbed skirt sections, one form effective for folding tableless skirt sections, and one form effective for folding skirt tabs, the tab folding folders being mounted inwardly of the remaining folders.

70 5. A mechanism for applying to containers skirted covers having alternate sections provided with tabbed ends comprising, a first folding means for initially folding down skirt sections in-

termidate the tabbed sections, a second folding means for thereafter folding down the tabbed sections with the edges of said tabbed sections overlying the adjacent edges of the respective intermediate sections and a third folding means for upwardly tucking the tabs between the skirt and container neck.

6. A mechanism for applying to containers skirted covers having alternate sections provided with tabbed ends comprising means for initially folding down skirt sections intermediate the tabbed sections, means for thereafter folding down the tabbed sections, and tucking means for folding the tabs upwardly between the skirt and container neck.

7. A mechanism for applying to containers skirted covers having sections provided with tabbed ends comprising skirt folding means, tab folding means for tucking the tabs upwardly between the skirt and container neck, and means for operating said skirt folding means initially to fold inwardly skirt sections, then to withdraw to permit freely the tucking of said tabs and thereafter to advance and finally compress the skirt sections.

8. A mechanism for applying to containers skirted covers having sections provided with tabbed ends comprising means for initially folding inwardly skirt sections, means for then tucking the tabs upwardly, and operating means to cause said skirt folding means to retract after the initial skirt folding to permit freely the tucking operation and thereafter to advance and finally compress the skirt sections.

9. A mechanism for applying to containers skirted covers having skirt sections provided with tabbed ends and skirt areas to be cemented together for securing the covers in place comprising tab folders for tucking the tabs upwardly between the skirt and container neck, skirt folders and pressers, and operating means for all of said folders, the order of operation being that the skirt folders initially press inwardly sections of the skirt and are then retracted a limited distance while the tabs are folded upwardly, and the skirt folders are then advanced to press the sections inwardly against the container and compress the cemented areas to effect final sealing.

10. The method of applying container covers to containers consisting in placing a cover blank having tabbed and untabbed sections defined alternately thereon over the mouth of a container, causing the untabbed sections to be folded downward relatively to the container mouth in advance of the tabbed sections which are also caused to fold downward relatively and forming pleats between the sections by bending on scored lines defining the pleats and by contact on certain of said lines, moving the ends of the tabs into contact with the container neck, moving said ends upwardly in contact with said neck until the tabs are inclined upwardly, then pressing on the part of the tabbed section adjacent the tab until the tab is moved upward and lies against the container neck between the same and the adjacent parts of the skirt, and finally compressing the parts all around the skirt to cause the cover to be secured on the container neck.

11. In a mechanism for applying skirted covers to containers, means for folding said skirt down around the container and for upwardly tucking a portion of the skirt, means for supplying cover blanks to the containers, and means for pre-bending sections of the skirt prior to the blank being engaged by said folding and tucking means.

12. In a mechanism for applying skirted covers to containers, means for folding the skirt against the container and for reversely tucking portions thereof between the skirt and container, means for supplying cover blanks to the containers, and means for pre-bending sections of the skirt prior to positioning of a blank adjacent to its container and prior to the tucking operation to assist in providing a free entrance for the tucked portions.

13. A mechanism for applying skirted covers to containers comprising means for folding the skirt against the container, means for tucking tab portions of the skirt between the skirt and container neck, means for supplying cover blanks to the containers and means associated with said supply means for pre-bending sections of the skirt prior to the location of a blank in position for operation of said folding and tucking means thereby to enable the tucked portions to enter between the skirt and container neck without substantial interference.

14. The method of applying hood covers to containers consisting in feeding a cover blank to a container, pre-bending the corners of sections adjacent tabs immediately before applying to the container, then placing the blank on the container mouth, supporting the blank over said mouth, folding down the sections and defining pleats therebetween pressing the untabbed sections inwardly more fully to define the pleats, pushing the depending tabs of tabbed skirt sections over the pre-bent corners, then folding the tabs upwardly between the container neck and the adjacent skirt parts, and finally compressing all of the skirt sections by pressure all around the skirt.

15. The method of applying covers to containers consisting in feeding a blank to a container, pre-bending the outer corners of untabbed cover sections immediately before applying the cover to the container, then placing the blank over the container mouth and pushing the latter upward against the blank and supporting the blank above the container mouth, folding down the sections of the skirt, forming a space between the container neck and the skirt, defining pleats between the sections and pressing the tabbed sections inwardly to assist in defining the pleats, pushing the tabs of the tabbed sections inward over the pre-bent parts of the untabbed sections and upward between the container neck and the adjacent skirt parts, and finally compressing all of the sections by pressure all around the cover.

16. In combination, in a container cover applying mechanism, a plurality of movable skirt folders arranged around the container axis, and a plurality of fixed pleat guides between said axis and said folders and cooperative with certain of the folders in forming a pleated cover.

17. In combination, in a container cover applying mechanism, a plurality of movable skirt folders, a plurality of fixed pleat guides, and a plurality of movable pleat pressers respectively adjacent the pleat guides, certain of the skirt folders without the pleat guides cooperative therewith and effective for actuating the pleat pressers.

18. Container cover applying mechanism embodying a plurality of movable skirt folders, a plurality of fixed pleat guides, and a plurality of movable pleat pressers, said guides and pressers being located within the skirt folders and cooperative therewith, certain of the folders effective to actuate the movable pleat pressers.

19. In a container cover applying mechanism, a plurality of movable skirt folders including certain folders adapted to engage alternate skirt sections and effect the initial folding of all the sections of the cover blank, fixed pleat guides to assist in forming pleats between said alternate sections and the intermediate sections, certain of said folders fixed against rotation around the container axis and effective for folding peripheral skirt tabs between the container neck and the adjacent skirt parts, and the remaining folders including those for the alternate sections effective to finally compress the skirt.

20. In a container cover applying mechanism, a plurality of folders adapted to engage alternate skirt sections and effect the initial folding of all the skirt sections, pleat forming means including fixed guides adapted to engage portions of cover between said sections effective for forming pleats between all the skirt sections, and means to complete the cover applying operation including a folder fixed against rotation around the cover axis and effective to bring a skirt tab between the container neck and the adjacent skirt parts.

21. Container cover applying mechanism embodying skirt folders of a plurality of forms, the folders of one form movable and each having a slot at its lower part, and the folders of another of said forms each having a portion movable in said slot of the folder of the first named form.

22. Container cover applying mechanism embodying skirt folders of a plurality of forms, the folders of one of said forms each having a slot in its lower part, and the folders of another form each having a bent lower part which is movable in said slot and adapted to fold skirt tabs.

23. Container cover applying mechanism embodying skirt folders of a plurality of forms, fixed supporting means for certain of said folders, said means having an under recess, and a movable folder support in said recess, certain of said folders being mounted on said movable folder support.

24. A two part folder for a container cover applying mechanism, comprising an actuating part consisting of a substantially straight lever of the first order having an actuating element at its upper end and an intermediate pivotal portion, and a folding part consisting of bent lever of the first order pivoted near its middle part to the lower end of the first mentioned lever, said second lever curved partially around its pivot, its lower end having a folding element, and resilient means between its upper end and the first lever.

25. A folder for use in a container applying mechanism comprising a pivotal portion, an actuating portion at one end, and a folding portion at the opposite end including an end surface to effect initial folding of a multi-sided cover blank and a pressing surface inward of said end surface.

26. In a container cover applying mechanism, a folder operating device which includes an up and down moving cam, a sleeve connected to and movable with said cam, an annular operating member slidable on said sleeve, a member automatically to move the annular member, and means connecting the sleeve and annular member permitting operation on containers of different sizes.

27. In a container cover applying mechanism, folder operating means which include an up and

down moving device embodying a sleeve, a flange thereon and a plurality of cam elements connected to the sleeve, an annular member slidable on said sleeve, means automatically to move the annular member, and means for connecting it with said flange.

10 28. In a container cover applying machine, blank strip feeding means including a rotary feeding member, ratchet mechanism connected with said member for rotating the same, a to-and-fro-moving member for operating the ratchet mechanism, and means to lock the to-and-fro-moving member during pre-determined operating conditions.

20 29. In a container cover applying machine, blank strip feeding means including a rotary strip feeding member, ratchet mechanism connected with said member for rotating the same, a slide to actuate the ratchet mechanism, and means to lock the slide during pre-determined conditions.

25 30. In combination, in a container cover applying machine, a base having an upright tube fixed thereon and secured against turning, an adjustable support member slidable in said tube, a cover applying head carried by means of said member, means to raise and lower said member, means for actuating said head, a drive means therefor extending up through said member, and means connected with the base for bringing containers into operative relation with said head.

30 31. In combination, in a container cover applying machine, a base member having an upright tube fixed thereon, a second tube slidable in said first tube and secured against turning, a cover applying head carried by means of said second tube, means for actuating said head, means to raise and lower the second tube including a screw threaded part thereof and a screw threaded tube within said second tube cooperative therewith, and means for bringing containers into operative relation with said head.

35 32. A container cover applying machine embodying a plurality of cover applying heads, a container supply conveyor, means for transferring a container from said conveyor to each of said heads simultaneously, a rotary cam actuator common to said heads, operative connections therefrom to each of said heads to operate the same in unison, individual means embodied in each of said heads for feeding a continuous strip of container cover blanks to the respective cover applying means, and means embodied in each head to stop the feed of blanks in the particular head when no container is presented.

40 33. In a container cover applying machine a pair of stationary heads with cover applying means therein, means for delivering uncovered containers to each of said heads simultaneously, a rotary cam actuator common to said heads, movable members adapted to receive motion from said actuator, connections from said members to the cover applying means in each of said heads to operate the same in unison, a source of cover blanks and feeding means therefor embodied in each head, and means in each head for stopping the feed of blanks independently of the other head when no container is presented to the particular head.

45 34. In a mechanism for applying skirted covers to containers, a cover applying head adapted to be arranged coaxially with and over the container, concentrically mounted cam means therein adapted to be shifted in said coaxial direction relative to the container, a series of pivoted fold-

ing fingers mounted around and adapted to engage said cam means, said fingers being of two types alternately arranged for folding corresponding skirt sections, means for so shifting said cam means relative to said folding fingers, the cam portions being shaped so that in the successive positions thereof the fingers of one type of fingers are in an advanced position to engage the corresponding skirt portions and effect a partial folding and then recede, and the other type of fingers then act to fold down the alternate skirt sections and thereafter all the fingers are advanced to complete the folding and compress the skirted sections.

35. In a machine for applying container cover blanks, a blank strip feeding means and a severing means for cutting off successively individual blanks from said strip combined with said feeding means, a to and fro actuating member connected to operate said strip feeding means, spring means for urging said actuating member in one direction, cam means for moving said actuating member in the opposite direction against said spring means, and means to lock said actuating member against return movement by the spring means during predetermined operating conditions.

36. A container cover applying machine embodying a pair of cover applying heads, a continuously moving endless container supply conveyor, means associated with said conveyor for positioning containers thereon near the cap applying heads in a predetermined spaced relation, and a transfer means for engaging a pair of said spaced containers and moving them from said conveyor to the cover applying heads.

37. A container cover applying machine embodying a pair of cover applying and securing heads, an endless moving belt conveyor for supplying containers, means for arranging successively the foremost pair of containers on said moving conveyor in predetermined spaced relation and for restraining them in such positions, and a transfer means for engaging the foremost pair in such spaced position and moving them to cover applying heads. 45

38. In a machine for applying container covers, cover folding means, a cam member arranged concentrically with said means adapted to reciprocate axially to operate said folding means, means for reciprocating said cam member, means for supplying cover blanks in strip form to the folder means, blank severing means, and an operating means for said blank severing means connected to be operated by the reciprocation of said cam member.

39. In a container cover applying machine, a pair of stationary heads with cover applying means therein, means for delivering uncovered containers to each of said heads simultaneously, 15 power actuating means, branch connections therefrom to the cover applying means in each of said heads normally to operate them in the same timed relation, a source of cover blanks and feeding means therefor embodied in each head, 20 and means in each head for stopping the feed of blanks independently of the other head when no container is presented to the particular head.

40. In a machine for applying covers to containers, a movable carrier, a support therefor, 25 said carrier being slidably mounted thereon, means for moving said support transversely, means for longitudinally moving said carrier on said support through said slidable mounting, and means for operating the two moving means in timed relation from a common source.

41. In combination, a plurality of stationary and spaced heads, each head having hood-folding fingers pivotally connected thereto, mechanism adapted to deliver hood-forming material 35 in the path of operating movement of said fingers, elevator devices located respectively in vertical registration with said heads, delivery means adapted to deliver unhooded bottles in vertical registration with said elevator devices, mechanism operable to raise said elevator devices and simultaneously to operate said fingers of each head successively during the upward movement of each bottle to fold a hood on each bottle.

ALBERT F. PITYO.
